BARBEQUE GRILL

John R. Madson, 2064 S. 98th St. 53227, and Donald Habermehl, 5136 W. Plainfield Ave. 53220, both of Milwaukee, Wis.

Filed June 4, 1973, Ser. No. 367, 074

Term of patent 14 years

Int. Cl. D7—02; D7—05

U.S. Cl. D7—107

FIG. 1 is a front elevational view of a barbecue grill showing our new design;

FIG. 2 is a top view thereof;

FIG. 3 is an end view, the opposite end being a mirror image thereof;

FIG. 4 is a rear elevational view; and

FIG. 5 is a perspective view showing the grill in open condition.

We claim:

The ornamental design for a barbecue grill, as shown and described.
